Miner + Rauher

UNITED STATES PATENT OFFICE

THOMAS E. MURRAY, OF BROOKLYN, NEW YORK; JOSEPH BRADLEY MURRAY, THOMAS E. MURRAY, JR., AND JOHN F. MURRAY, EXECUTORS OF SAID THOMAS E. MURRAY, DECEASED, ASSIGNEES TO METROPOLITAN ENGINEERING COMPANY, A CORPORATION OF NEW YORK

BOILER WALL

Application filed January 10, 1929. Serial No. 332,143.

This invention relates to boilers and in particular to an improved type of wall including a series of hollow tubes provided with anchorage members adapted to be imbedded in a body of insulating material forming part of the wall.

An embodiment of the invention is illustrated in the accompanying drawing in which—

10 Fig. 1 is a horizontal section through one portion of the boiler wall;

Fig. 2 is a face view of the boiler wall with parts broken away in interest of clearness;

15 Fig. 3 is a detailed view illustrating a modification.

Referring in detail to the drawing, my improved boiler wall includes a series of tubes 10 arranged alongside one another, each tube having detachably secured thereto an anchorage member 12 extending lengthwise of the tube and arranged with one edge adjacent the tube. Each anchorage member is formed with a plurality of angular extensions 14 which are conveniently formed by bending alternate portions of the plate from which the anchorage is formed to bring it substantially at right angles to the flat face of the member.

20 The anchorage members are detachably secured to the tubes 10 by means of clips 16, the portions 18 of which are curved to fit the cylindrical surface of the tube. These clips are provided with rearwardly extending portions 25 which are apertured to permit the passage therethrough of bolts 22 by which the clips are snugly clamped against the tubes. The clips are preferably bevelled as at 24 so as to provide a clearance space 26 between the surface of the member 12 and the inner portion of the clip so that when the nut 27 is tightened up on the bolt each clip fulcrums on the corner 28 bearing against the surface of the anchorage member 12. Thus a pinching action is exerted on both the tube and the anchorage member. The anchorage members 12 are imbedded in a body of insulating material 30. And between the tubes in some cases I provide a thin sheet of iron or other suitable metal indicated at 32. This may be 30 in the form of perforated plates as shown or

may be expanded metal lath or the like which is provided with openings to permit cementitious or plastic material to be integrally keyed to the plate. To the surface of the plates 32 opposite the insulating body, I also apply a 35 layer of fire-resistant cement 34 and as indicated at 36, I preferably build a layer of cement to cover the exposed ends of the clips 16.

In the construction above described the 40 clips make a friction grip on tubes 10 and the ends of the clips extend beyond the diametral faces of the tube. Instead of this arrangement I may provide the alternative construction shown in Fig. 3 wherein the tubes 10a are provided with outwardly extending lugs 10b 45 which coact with recesses 18a formed in modified clips 18b. With this arrangement there is provided a positive interlock between clips 18b which does not depend upon having the ends of the clips extend beyond the diametral 50 points of the tube.

In a previous application No. 642,427 filed 55 May 31, 1923, I have illustrated a tubular boiler wall with refractory material on the outside having an imbedded reinforcement 75 which is secured to the tubular structure; and have claimed the combination generally. Such a combination of a tubular water-wall with insulating material applied to the outside of it, has important advantages set out 60 in the aforesaid application.

The present invention represents an improvement in ease and rapidity of erection of 65 such walls by the use of comparatively simple devices for attaching the anchorage members to the tubes. The attaching means is 70 a clamp of comparatively small cost which we can afford to imbed in the insulating material.

Also in a previous application No. 61,386 of 75 October 9, 1925, I have described and claimed the use of tubes having flanges thereon which are imbedded in the outer plastic material.

While I have described quite specifically 80 the structural details of the embodiment of the invention illustrated, it is to be understood that various modifications may be 85 made by those skilled in the art without departing from the invention as defined in the 90 appended claims.

What I claim is:—

1. A boiler wall comprising a plurality of tubes arranged alongside one another, an insulating body adjacent the tubes, anchorage members extending lengthwise of the tubes and clamp members fulcruming on said anchorage members at spaced intervals for securing the tubes to said anchorage members with a friction grip. 5
10. 2. A boiler wall comprising a plurality of tubes arranged alongside one another, an insulating body adjacent the tubes, anchorage members comprising elongated plates whose inner edges point toward the centers of the tubes and having anchorage projections extending from their outer edges and detachable clips for securing said anchorage members to said tubes. 15
20. 3. A boiler wall comprising a plurality of tubes arranged side by side, a body of insulating material filling the space between the tubes, anchorage members embedded therein, clips detachably secured to both the tubes and the anchorage members. 25
30. 4. In a boiler wall of the character described the combination of an anchorage member extending lengthwise of the tube, a clip having one portion arranged to neatly fit the tube and another portion constructed and arranged to fulcrum on said anchorage member and means for clamping said clip to said anchorage member. 35
35. 5. A boiler wall comprising a plurality of tubes arranged side by side with spaces between them, metal lath between said tubes, a body of insulating material engaging said lath and said tubes on one side and a body of heat resisting cement between said tubes on the opposite side of said lath, and anchorage members imbedded in said insulating body and means for securing the anchorage members to said tubes. 40
45. 6. A boiler wall comprising a plurality of tubes arranged side by side with spaces between them, metal lath between said tubes, a body of insulating material engaging said lath and said tubes on one side and a body of heat resisting cement between said tubes on the opposite side of said lath, and anchorage members extending lengthwise of said tubes comprising plates having angular projections extending therefrom and imbedded in said insulating body, clips having portions which fulcrum on said anchorage members 50
55. and means for clamping said clips to both the tubes and the anchorage members. 55
60. 7. A boiler wall comprising a plurality of vertically extending tubes alongside of one another, anchorage members having elongated webs attached to the tubes with the inner edge of the web adjacent to the tube, and an insulating body over the outer side of said tubes, said anchorage members having at the outer portion of their webs lateral extensions embedded in said insulating body 65
- and serving to support and hold it against falling away from the tubes. 70
8. A boiler wall comprising a plurality of vertically extending tubes alongside one another, an insulating body over the outer side of said tubes, and means for supporting said insulating body from said tubes comprising separate anchorage members frictionally secured to said tubes. 75
9. A boiler wall comprising a plurality of vertically extending tubes alongside one another, an insulating body over the outer side of said tubes, anchorage members embedded in said insulating body and clips connected to said anchorage members and directly and detachably engaging the tubes and exerting a friction grip thereon. 80
10. A boiler wall comprising a plurality of vertically extending tubes alongside one another, an insulating body over the outer side of said tubes, anchorage members embedded in said insulating body and securing clips detachably connected to said anchorage members and directly and detachably engaging the tubes, the clips and the tubes having complimentary interlocking portions. 85
11. A boiler wall comprising a plurality of vertically extending tubes alongside one another, an insulating body over the outer side of said tubes, anchorage members embedded in said insulating body and clips each having a seat portion which detachably engages only a portion of the periphery of a tube and means detachably securing said clips to said anchorage members. 90
- In witness whereof, I have hereunto signed my name.
- THOMAS E. MURRAY.
